UNITED STATES PATENT OFFICE.

RICHARD D. WYCKOFF, OF NEW YORK, N. Y.

PROJECTOR COMBINED WITH PRINTING MECHANISM OF TICKERS OR OTHER INSTRUMENTS.

1,424,228.

Specification of Letters Patent. Patented Aug. 1, 1922.

Application filed July 24, 1919. Serial No. 312,976.

To all whom it may concern:

Be it known that I, RICHARD D. WYCKOFF, a citizen of the United States, residing at New York, in the county of New York and State of New York, have invented certain new and useful Improvements in Projectors Combined with Printing Mechanism of Ticklers or Other Instruments, of which the following is a specification.

10 The objects of my invention are to provide mechanism for publishing or exhibiting to an audience reports such as furnished by a news or "stock ticker," and to provide this apparatus in simple and inexpensive 15 form, readily attachable to a "ticker" of the character now in general use.

Stated briefly, the invention consists of a projector which is combined with the printing mechanism of the ticker or other 20 instrument in such a way as to project a picture of the record, as it is made, onto a screen where it can be easily read by those interested.

The particular improvement to which this 25 present invention is directed is in the more advantageous combination or association of the projector device with the ticker, the projector being housed within a hollow support on which the ticker is mounted. Another 30 feature of improvement is the very simple means by which the ticker tape is led through the printing mechanisms of the ticker and also through the projector.

Other objects and aims of the invention, 35 more or less broad than those stated above, together with the advantages inherent, will be in part obvious and in part specifically referred to in the course of the following description of the elements, combinations, arrangements of parts, and applications of 40 principles constituting the invention; and the scope of protection contemplated will appear from the claims.

In the accompanying drawings, which are 45 to be taken as part of this specification, and in which I have shown merely a preferred form of embodiment of invention, Figure 1 is a front elevation, with parts broken away, illustrating a form of embodiment of my invention; and Figure 2 is a sectional view taken on the line 2-2 of Figure 1, looking in the direction of the arrows, and with parts broken away.

In the present disclosure, a printed rec-

ord, which is also to be projected onto a 55 screen, is furnished by a ticker 4, the same being indicated as of conventional design, and provided with printing mechanism in the form of cooperating impression-producing members 5 and 6, between which the 60 record tape, which may be of paper as usual, is led, from a roll or reel 7, the record strip being indicated by the reference character 8. This reel of tape is carried on a bracket 9 which extends upwardly from a 65 hollow base 10 on which the ticker 4 is carried. The tape 8 advances over a roller 11, between the printing devices 5 and 6 over a roller 12, thence downwardly into the interior of the hollow base 10, around a 70 roller 14 horizontally through the top portion of the hollow base 10 between two pressure rollers 15 and 16, one of which, as for instance 16, is positively driven by means of cooperative connection with moving parts 75 of the ticker, and thence out through an aperture 17 in the side wall of the hollow base 10, so that as the ticker operates the tape is correspondingly and appropriately pulled through the field of operation of the 80 printing mechanisms 5 and 6 and through the top part of the hollow base whence it is discharged to the outside. The course of the tape through the hollow base is substantially horizontal as shown, and within 85 the hollow base in proper relation is mounted a lamp 18 with a reflector 19 whereby the rays from the lamp 18 are directed against the tape as it travels through the housing. 90 20 indicates a first surface mirror adapted to reflect the image of the moving or stationary tape which passes through the housing, into the lenses 21 and 22 for projection onto a suitable screen in a well understood manner.

By means of this apparatus I am enabled to provide a projecting apparatus in immediate association with a ticker and with the minimum number of parts and with the greatest possible saving of space.

I claim:—

1. In combination with a ticker or the like, a hollow supporting base therefor, a projecting lens mounted in said hollow base, a reflector in the hollow base and disposed to 105 cast an image into said lens, means for feeding and for supporting a length of the record printed by the ticker in the hollow

95

100

base in position to be reflected by the reflector and a lamp in the hollow base disposed to illuminate the section of record supported within the hollow base.

- 5 2. In combination with a ticker or the like, a hollow supporting base for the same, means for supporting a length of the ticker record substantially horizontally within the hollow base, a reflector within the base and beneath said supported length of ticker record, a projecting lens in front of said reflector and a lamp within the base behind the reflector and disposed to illuminate the face of supported length of record.
- 15 3. In combination with a ticker or the like, a hollow supporting base for the same, means for supporting a length of the ticker record substantially horizontally within the hollow base, a reflector within the base and beneath said supported length of ticker record, a projecting lens in front of said reflector and a lamp within the base behind the reflector and disposed to illuminate the face of supported length of record, and a
- 20 25 reflector behind the lamp for throwing the

light therefrom onto said supported portion of the record.

4. In apparatus of the character described, a lamp house, a ticker mounted on said lamp house, means for feeding a length of the record from the ticker into and across the upper portion of the lamp house, means for illuminating the face of said length of record within the lamp house, a projecting lens, and a first surface reflector disposed to throw the image of said illuminated length of record into said projecting lens.

5. An apparatus of the character described, comprising a hollow base, a projecting lens mounted in one of the walls of said base, a reflector in the hollow base and disposed to cast an image into said lens, means for supporting a length of printed strip in the hollow base in position to be reflected by the reflector, and a lamp in the hollow base behind the reflector to illuminate the face of the supported length of printed strip.

In testimony whereof I affix my signature.

RICHARD D. WYCKOFF.
